UNITED STATES PATENT OFFICE

2,178,360

COAL FEEDING DEVICE FOR FURNACES

George A. Kohout, Chicago, Ill.

Application March 6, 1936, Serial No. 67,471

3 Claims. (Cl. 110—110)

This invention relates to coal feeding devices for furnaces and particularly to such feeding devices as are adapted to feed the fuel into the furnace and to distribute the same over the grate 5 in the furnace while it is falling.

In my prior Patent No. 1,698,135, a method of feeding fuel is disclosed which consists in the spreading of the fuel over the furnace grate by striking it with a fluid blast while falling.

10 The present invention is an improvement over the device disclosed and claimed in the aforesaid patent in that it provides a simplified and more effective method of supplying the coal to the furnace and furthermore takes advantage 15 of certain characteristics of a screw type of fuel feeding device to facilitate the spread of fuel over the furnace grates.

The invention further includes a novel structure of fuel feeding device whereby the fuel is 20 not only advanced into the furnace by means of the fluid blast but has imparted thereto a forward momentum which aids the fuel blast in distributing the particles farther into the furnace chamber.

25 The invention contemplates also the provision in a fuel feeding device of this character of a novel hopper structure which cooperates with the particular fuel feeding device to provide for ready accessibility to all the parts of the mechanism.

30 It is a further purpose of the invention to provide a fuel feeding device wherein the parts are adequately protected from the dust and coal particles and are also so contained as to prevent, 35 to a great extent, danger of accident to the operators attending the furnace.

More specifically, the invention contemplates 40 the provision of a fuel feeding device having a hopper which can be opened up to provide ready access to the bottom thereof in combination with fuel feeding screws operating in the hopper in timed relation to each other to advance fuel to an inclined inlet opening to the furnace where the fuel is struck by a fluid blast for the purpose 45 of scattering it over the grates of the fire box of the furnace.

Other and more specific objects and advantages of the invention will appear as the description proceeds in connection with the accompanying drawings. It is to be understood, however, that the drawings and description are 50 illustrative only and are not to be taken as limiting the invention except in so far as it is limited by the claims.

55 In the drawings—

Fig. 1 is a vertical section in part diagrammatic and taken longitudinally of a furnace to which the fuel feeding device has been applied;

Fig. 2 is a front elevation of the fuel feeding device with the front cover therefor opened up; 5

Fig. 3 is a plan section showing the fuel feeding device as mounted upon the furnace;

Fig. 4 is an enlarged section taken on the line 4—4 of Fig. 2;

Fig. 5 is an enlarged sectional view taken on 10 the line 5—5 of Fig. 2;

Fig. 6 is a diagrammatic perspective view of the fuel feeding device illustrating the manner in which it is protected;

Fig. 7 is a sectional view taken substantially 15 on the line 7—7 of Fig. 2;

Fig. 8 is an enlarged sectional view through the driving mechanism of a fuel feeding unit;

Fig. 9 is a front elevational view of driving means for the feeding unit; and 20

Fig. 10 is a view on the line 10—10 of Fig. 1.

Referring now in detail to the drawings, I have shown the invention as applied to a furnace having a fire box 10 beneath a boiler 11. Within the fire box 10 there is provided a grate 12 which 25 separates the fire box combustion zone from an ash pit 13. The furnace is provided at its front with one or more lower doors such as 14 for access to the ash pit and with one or more over fire doors 15 which provide access to the fire box 30 10 above the grates 12. The present invention concerns itself with mechanism for delivering fuel into the fire box 10 and spreading the fuel as it is delivered over the grates 12.

At the front of the furnace there is usually 35 provided a metal facing or covering 18 in which the doors such as 14 and 15 are mounted. Adjacent to this metal facing and above the doors 15, I mount a channel iron 19 which, as it is shown in cross section in Fig. 4, has a flange 20 40 that is secured directly to the facing 18, as for example by suitable bolts 21. The channel iron 19 also has a vertical portion 22 turned down at its outer edge, and at the lower edge of the portion 22 the channel iron is again turned out- 45 wardly as indicated at 23. The channel iron is supported at its opposite ends by a pair of legs 24 and 25 which legs are bolted preferably to the portion 22 of the channel iron. This channel iron 19 forms a hopper bottom and a mount- 50 ing portion for the fuel feeding mechanism as well.

Bolted to the portion 22 of the channel iron 19 is a horizontally running plate 26 which projects up above the channel iron. At the upper 55

edge of the plate 26, there is hinged a plate 27 which forms an upward extension for a front wall of the fuel hopper. At the left hand end of the fuel hopper, a plate 28 is mounted. This plate is secured to the facing 18 by a suitable angle bar 29 fastened by screws both to the plate 28 and the facing 18. A second angle bar 30 is secured at the forward edge of the plate 28 and forms a shoulder against which the sloping front plate 27 rests when in its raised position. A second plate 31 is secured in position at the right hand side of the fuel feeding device by angle bars 32 and 33. The angle bar 33 operates in the same manner as the angle bar 30 to provide a stop for the front plate 27.

The front of the drive mechanism for the fuel feeding device is closed below the plate 27 by a hinged front cover section 34 which extends across the front of the furnace and is hinged to the horizontally projecting portion 23 of the channel iron 19. The plate 27 carries an inverted V-shaped strip 35 to which the section 34 may be secured by suitable wing nuts such as 36 and 37 engaging bolts which project from the strip 35. Similarly, wing nuts 38 and 39 are utilized to secure the plate 27 in raised position. The section 34 does not extend all the way to the right hand end of the furnace, but is supplemented by a separate section 40 which is hinged to the portion 23 and is secured by a suitable locking device 41 to a front plate 42 which extends from the end plate 31 of the hopper outwardly to the end of the fuel feeding casing.

The front plate 42 is part of an end housing 43 which extends down over the end of the channel iron 19 as shown best in Fig. 6. The end housing 43 extends vertically substantially to the top of the hopper end plate 31 and has a top portion 44 (see Figs. 6 and 7) that extends over to meet the hopper end plate 31. A door 45 is provided in the end of the housing 43. This door is provided with a suitable latch mechanism indicated at 46. Also, the housing 43 has a top door 47. Thus access is readily obtained from three sides into the interior of the housing 43. The door 40 may be opened for access at the front. The door 45 may be opened for access at the end, and the door 47 may be opened for access at the top.

From the above description, it is believed to be evident that the entire fuel feeding mechanism is fully housed and protected. The housing furthermore forms a part of the hopper structure, the plate 27 being a cover for the driving means for the fuel feeding mechanism, as will be more clearly explained hereinafter. Also, the housing 43 cooperates with the end plate 31 to enclose a damper regulator mechanism 48 and a suitable drive mechanism 49 for the fuel feeding device. As shown best in Fig. 4, the hinged section 34 may be let down to permit dropping the front plate 27 of the hopper whereby ready access is obtained to the fuel feeding parts that are exposed in the hopper.

The mounting of the fuel feeding mechanism upon the channel iron 19 and upon the plate 26 will now be described. Referring to Figs. 3 and 4 in particular, it will be observed that there are a plurality of pairs of brackets 50 and 51 spaced lengthwise of the channel iron 19. Each of these brackets is bolted by means of a suitable bolt 52 to the front plate 26, then they are bolted by means of a pair of bolts 53 and 54 to the channel iron 19. These brackets serve also to secure a plurality of feed screw housings 55, 56, and 57

to the channel iron 19. The front wall of the furnace is provided with a plurality of inlet openings into which the feed screw housings 55, 56, and 57 extend. The facing 18 is utilized as one wall of the hopper and has openings cut therein through which the housings 55, 56, and 57 extend. As a matter of strengthening the structure, an angle iron 58 may be provided opposite the flange 20 of channel iron 19 to aid in supporting the fuel feeding mechanism. The several brackets 50 and 51 thus serve to unite the front plate 26 with the channel iron 19 and the housings 55, 56, and 57 in such a manner as to produce a substantially rigid assembly. This is highly desirable in order that no difficulties will be encountered due to the housings being out of line with the front plate 26 which carries a feed screw operating mechanism for turning feed screws in the housings 55, 56, and 57.

The feed screw mechanism constitutes a plurality of feed screws 59, 60, and 61 which feed screws overlie forwardly extending portions of the housings 55, 56, and 57 that are held down by the brackets 50 and 51. Each feed screw is provided with a polygonal socket at 62 (see Fig. 8) which socket receives a polygonal head 63 on a drive shaft 64. A pin 65 is utilized to secure the feed screw to its drive shaft.

The drive shaft 64 is supported on a bearing block 66 which is bolted by suitable screw bolts 67 to the front plate 26. The shaft 64 has an enlarged bearing portion 68 that seats in a bearing 69 carried by the block 66. Suitable oil grooves 70 and 71 are provided in the bearing 69. The shaft 64 projects beyond the block 66 and is provided with a sleeve 72 on which there is mounted a rocker arm 73. The rocker arm 73 is adapted to be rocked to and fro by a suitable power mechanism to be hereinafter described. This arm has a hub portion 74 rotatable on the sleeve 72. The hub portion 74 carries a projection 75. A pivot pin 76 is bolted to the projection 75 by a screw threaded extension 77 thereof, and this pivot pin carries a pawl 78.

A ratchet wheel 79 fits on the shaft 64 and is connected thereto by a connecting block 80 which is rigidly secured to the shaft 64 by a shear pin 81 that may be sheared off in event of excessive strain. The block 80 is connected to the ratchet wheel 79 by a second pin 82. It is understood, of course, that the pin 82 which connects the block 80 and the ratchet wheel 79 is stronger than the shear pin 81 so that in the event of excessive strain the point of breakage would be at the shear pin 81.

The pawl 78 is controlled in its engagement with the ratchet wheel 79 by means of a shield which comprises a plate 83 pivoted on the shaft 64 between the ratchet wheel 79 and the hub 74. This shield has a flange 84 which projects over the ratchet wheel 79 so as to prevent the pawl 78 from contacting the teeth of the ratchet wheel. The shield is adjustable to expose different numbers of the ratchet wheel teeth to the action of the pawl 78 by rotation of the shield about the shaft 64. For this purpose, the plate 83 is notched at 85 about its periphery and a pin 86 is mounted on the bearing block 66. This pin 86 is adapted to seat in any desired one of the notches 85 and to hold the shield flange 84 in any desired position with respect to the pawl 78.

The foregoing description, while confined to one drive unit only, applies to the several drive units for driving the three feed screws 59, 60, and 61. For convenience in tracing the numbering, 75

the drive units will be referred to as 59', 60', and 61'.

It will be noted, by reference to Fig. 2, that the pawl 78 for the drive unit 60' is pointed in the opposite direction to the pawls 78 for the drive units 59' and 61'. Similarly, the teeth of the ratchet wheel of the drive unit 60' are reversed so that, when rocking movement is imparted to the respective arms 73 of the drive units, the drive unit 60' will operate to turn its screw 60 in the opposite direction to the rotation of the screws 59 and 61'. The power required to turn the screw 60 is also required during the time when the screws 59 and 61 are at rest.

15 , The several arms 73 are connected to a driving bar 87 so that they are rocked in unison by reciprocation of this bar. The connection of each arm 73 to the drive bar 87 is made by means of a bolt 88 and a bearing sleeve 89 together with 20 a washer 90. This construction is best shown in Fig. 8. The bar 87 has a link 91 pivoted thereto, and this link is connected to the lower end of a rocker arm 92 by means of a pin and slot connection consisting of a slot 93 in the arm 92 and 25 a bearing pin 94 for the link 91 which bearing pin can be adjusted to vary the length of stroke given to the bar 87 for any fixed angular movement of the rocker arm 92. The rocker arm 92 is pivoted on a standard 95 that is carried by a plate 96 (see 30 Fig. 2) that is mounted on the channel iron 19. A link 97 connects the upper end of the rocker arm 92 with a pin 98 on a disk 99 that is rotated by the drive unit 49.

The drive unit 49 comprises a reduction gear 35 of any well known type and received its power from a drive pulley 100. The drive pulley 100 is driven by a belt 101 from a pulley 102 on a motor 103. The motor 103 is suspended from the channel iron 19 in the manner shown in Fig. 7 by 40 means of a bracket 104. The motor has a base 106 that is hinged to the bracket 104 and adjustably connected to the part 23 of channel iron 19 by a bolt 107 and suitable lock nuts 108 and 109. By means of the bolt 107, the motor 45 can be raised and lowered to obtain the proper tension upon the belt 101. The reduction gear unit 49 is supported upon a plate 110 which is mounted on the channel iron 19.

The drive unit 49 also drives a second reduction gear unit 111 by means of a shaft 112, and this reduction gear unit 111 operates a disk 113 to which a damper control link 114 is eccentrically pivoted. The link 114 is the means for operating a damper regulator 48 which is of the type 55 disclosed in my prior Patent No. 1,875,616. The damper regulating mechanism indicated generally by the numeral 48 is adapted to be connected by a flexible cable or similar arrangement to a damper in the furnace stack. As shown in my 60 prior patent just referred to, this connection is made to the member 48' of the damper regulator. The operation of the damper regulator 48 is the same as that disclosed in the above mentioned patent. Therefore, the details of its operation 65 will not be described in the present application.

The bar 87 in addition to operating the several feed screws is also utilized to operate a shaker device for shaking down the coal in the fuel hopper. Referring now to Figs. 2 and 5 in particular, it will be noted that the bar 87 has a pin 115 mounted thereon between its connection to the units 59' and 60'. This pin is adapted to engage a forked arm 116 that is secured to a shaft 117 by a shear pin 118. The shaft 117 is 70 mounted in a bearing 119 that is bolted to the

plate 26. The bearing 119 is an elongated sleeve bearing which has a flange 120 through which suitable screw bolts 121 are passed to mount the bearing upon the plate 26. Within the hopper over the channel iron 19, the shaft 117 has a hub 122 secured thereto by a pin 123. The hub 122 has an annular flange 124 thereon. A bar 125 extends lengthwise of the hopper and is secured to the flange 124 by a rod 126 which is pivoted in a bearing member 127 seated in an opening in the flange 124. Suitable collars 129 and 130 are fixed on the rod 126 to hold the bar 125 in position, and the rod 126 has the oppositely projecting extensions 131 and 132 that are adapted to move to and fro in the coal in the hopper 15 so as to prevent the same from clogging. The bar 125 is also supported between the drive units 60' and 61' by a second shaft 133 that is supported by a bearing block 134 also secured by suitable screw bolts to the plate 26. The shaft 133 carries a disk 135 that is connected to the bar 125 by a rod 136 in the same manner as rod 125 connects the flange 124 to the bar 125. The opposite ends of the bar 125 have triangular loops 137 and 138 therein for shaking the coal 25 at the ends of the hopper.

The operation of the coal shaking mechanism is as follows: The bar 87 in reciprocating causes the pin 115 to strike first one side and then the other of the forked end of the arm 116 so as to move this arm first in one direction and then in the other. This motion is communicated to the bar 125 and its rods 126 and 136 by means of the shaft 117 so as to oscillate the bar 125 in the hopper.

Referring now to Figs. 3 and 4 in particular, the mechanism whereby the fuel is introduced into the fire box through the housings 55, 56, and 57 will be described. Each of these housings is preferably cast with a bottom extension 140 40 that projects over the channel iron 19 and beneath the screws so that it may be secured firmly in place by means of the brackets 50 and 51. From the face plate 13 toward the fire box, the housing has a tubular portion 141 into 45 which the feed screw extends, and this tubular portion may desirably have a rounded or semi-cylindrical interior on the lower half thereof. Adjacent its fire box end, the tubular portion is cut away both at the bottom and at the end as indicated at 142 and 143 to provide a fuel discharge opening 144. The inner end of the tubular portion 141 is partly closed by a wall 145, and this wall carries a refractory supporting bracket 146 cast integral therewith.

Beneath each housing 55, 56, and 57, there is provided a second casting 147 which casting rests upon refractory material 148 at the front of the fire box and supports the tubular portion 141 of each housing. This casting 147 is hollow, as indicated in the sectional view in Fig. 1. At the fire box end of the casting 147, the top thereof is stopped at the terminal edge 142 of the tubular portion 141 of the housing and slopes downwardly as indicated at 149 to provide a sloping shelf 45 down which the fuel rolls as it is fed through the housing by the feed screw. The slope of the face 149 may, of course, be varied within reasonable limits, but it preferably makes an angle of about 45° to the horizontal. The casting 147 50 has a flat slit opening 150 at the lower edge of the sloping face 149, and directly beneath this opening there is inserted a cast iron plate 151 that may be adjusted in and out and which serves as a landing where the coal particles strike 55

and rebound after they roll down the sloping face 149.

A fluid injector 152 is mounted in the interior of the casting 147. The details of this injector are more clearly explained in my copending application Serial No. 67,470, filed March 6, 1936. The function of the device 152, however, is to direct a fluid blast through the opening 150 so as to strike the coal which has already been given a forward impetus by its rolling down the sloping face 49 and bounding off of the plate 151. The effect of the fluid blast striking the moving particles of fuel is to give them more speed in a horizontal direction so as to drive them out into the fire box and to drive the fine particles which are more susceptible to the fluid blasts farther out into the fire box than the coarser particles are driven. The blast is powerful enough to drive most of the dust and real fine particles out into the fire box without their striking the plate 151. However, the larger particles have enough momentum from rolling down the inclined face 149 to cause them to engage the plate 151 and rebound upwardly. By this action of the larger particles, they are held under the influence of the fluid blast long enough to give them a substantial throw into the fire box.

The resultant distribution of the fuel over the grates is not a complete separation with all of the coarser particles closer to the front of the fire box. In fact, the particles which are just too fine to gain enough momentum to strike the plate 151 often times fall to the grate more closely to the front of the furnace than the larger particles which rebound off of the plate 151. Thus a resultant intermingling of coarse and fine particles occurs over most of the grate surface. At the extreme front end of the grates where burning of the fuel is naturally at a low rate, because of the proximity of the fuel to the front structure of the fire box, very little fuel is deposited.

In order to protect the housings such as 55, 56, and 57 from the heat within the fire box, the fuel outlet 144 is shielded by means of a special refractory tile 153 that is provided with a T slot adapted to receive the bracket 146 on the end of the housing. A pair of side tile 154 and 155 is mounted alongside the refractory tile 153, and these tile, as shown by Fig. 1 and Fig. 3 extend back over at least half the length of the tubular portion 141 of each housing. A cap tile 157 covers the tile 153.

The fluid blast supplied by the member 152 may be from any suitable source. For example, I have shown a steam supply pipe 156 (see Fig. 1) leading to a nozzle 157 that is directed into the member 152 so as to act as an injector and to draw in a substantial blast of air mixed with steam which blast is then driven through the opening 150 and utilized to spread the coal in the fire box.

From the above description, it is believed that the construction and operation of this de-

vice will be readily apparent to those skilled in this art.

Having thus described one specific form of my invention, what I claim as new and desire to secure by Letters Patent is:

1. A coal feeding device for furnaces comprising in combination, a fire box having a grate therein and having a front wall provided with a fuel inlet to the front of the fire box, a feed screw housing extending into and communicating with said inlet, a hopper outside the fire box at the front thereof and having an opening into said housing, a feed screw in said hopper and extending into said housing, means to rotate said screw and thereby advance fuel from said hopper into the housing, said hopper having a front wall extending over the screw rotating means, said front wall being pivotally mounted at its lower edge and foldable down over the screw rotating means to provide ready access to the screw in the hopper, a support for said hopper beneath said screw means mounting said screw, rotating means on said support, a cover for the front of said screw rotating means hinged at its lower edge to said support, and means detachably securing said cover at its upper edge to the front wall of the hopper. 15 20 25

2. A coal feeding device for furnaces comprising in combination, a fire box having a front wall provided with a plurality of fuel inlets to the fire box, feed screw housings extending into and communicating with said inlets, a hopper in front of said wall having openings into said housings, a channel iron fixed to the front wall and providing a support for said hopper, feed screws in said hopper and projecting into said housings, means to rotate said feed screws, a plate fixed to said channel iron, said screw rotating means being mounted to said channel iron by said plate, brackets connecting said housings and said plate 35 to said channel iron, the front wall of said hopper being hinged to said plate, and a front cover for the screw rotating means hinged to said channel iron and having an individual door 40 therein in front of each of said feed screws. 45

3. A coal feeding device for furnaces having a fire box having a grate therein and having a front wall provided with a plurality of fuel inlets to the front of the fire box, said coal feeding device comprising a hopper at the front of the fire box, a support for said hopper adapted to be secured to said front wall, a plurality of feed screw housings extending into said fuel inlets and communicating therewith, feed screws in said hopper and extending into said housings, screw rotating means carried by said support for advancing fuel from the hopper into said housings, said hopper having a front wall extending over the screw rotating means, and said front wall being pivotally mounted at its lower edge and foldable down over the screw rotating means to provide ready access to the screws in the hopper. 50 55 60 65

GEORGE A. KOHOUT.
